UNITED STATES PATENT OFFICE

HARRY N. NUNIMAKER, OF GROVETON, PENNSYLVANIA

DESIGN FOR A DOG FEEDING TABLE

Application filed May 28, 1932. Serial No. 43,929. Term of patent 3½ years.

To all whom it may concern:

Be it known that I, HARRY N. NUNIMAKER, a citizen of the United States, residing in Groveton, in the county of Allegheny and State of Pennsylvania, have invented a new, original, and ornamental Design for a Dog Feeding Table, of which the following is a specification, reference being had to the accompanying drawing, forming part thereof, in which—

Figure 1 is a front elevation of my dog feeding table;

Figure 2 is a top plan view thereof; and Figure 3 is an end elevation.

What I claim is:

The ornamental design for a dog feeding table, as shown.

Signed at Groveton, in the county of Allegheny, and State of Pennsylvania, this 9th day of May, 1932.

HARRY N. NUNIMAKER.
